US00D456712S

(12) **United States Design Patent** (10) Patent No.: **US D456,712 S**
Krich (45) Date of Patent: **** May 7, 2002**

(54) **BOTTLE WITH INTEGRATED GRIP PORTION**

(75) Inventor: **Jeffrey D. Krich**, Orland Park, IL (US)

(73) Assignee: **Crown Cork & Seal Technologies Corporation**, Alsip, IL (US)

(**) Term: **14 Years**

(21) Appl. No.: **29/097,417**

(22) Filed: **Dec. 7, 1998**

(51) LOC (7) Cl. **09-01**

(52) U.S. Cl. **D9/434; D9/542; D9/569**

(58) Field of Search **D9/542, 543, 434, D9/556, 566, 569, 520, 568, 570; 215/382, 383, 384**

(57) **CLAIM**

The ornamental design for a “bottle with integrated grip portion,” as shown and described.

DESCRIPTION

FIG. 1 is a top isometric view of this invention of a bottle with integrated grip portion;

FIG. 2 is a front elevation view of FIG. 1;

A rear elevation view is identical to the view of FIG. 2;

FIG. 3 is a side elevation view of FIG. 1;

A second side elevation view is identical to the view of FIG. 3.

FIG. 4 is a top plan view of FIG. 1; and,
FIG. 5 is a bottom plan view of FIG. 1.

The broken lines in the drawings are for illustrative purposes only and do not form part of the claimed design.
